GEORGE H. KRAUSKOPF, OF PITTSBURGH, PENNSYLVANIA, ASSIGNOR TO WESTINGHOUSE ELECTRIC AND MANUFACTURING COMPANY, A CORPORATION OF PENNSYLVANIA.

SUPPORT FOR ARMATURE CROSS-CONNECTORS.

1,229,759.

Specification of Letters Patent. Patented June 12, 1917.

Application filed January 15, 1913. Serial No. 742,144.

To all whom it may concern:

Be it known that I, GEORGE H. KRAUSKOPF, a citizen of the United States, and a resident of Pittsburgh, in the county of Allegheny and State of Pennsylvania, have invented a new and useful Improvement in Supports for Armature Cross-Connectors, of which the following is a specification.

My invention relates to dynamo-electric machines, and it has special reference to cross-connectors for armature conductors and to supporting means for such connectors.

The object of my invention is to provide a compactly-nesting and readily constructed set of cross-connectors, which, together with suitable supporting means, shall form a permanent unit adapted for ready attachment to the frame of the machine. Heretofore, cross-connectors have been constructed and assembled in a very different way from that hereinafter described, and have not embodied a similar detachable feature.

According to my present invention, I provide a set of nesting cross-connectors severally disposed on edge and permanently bound with wire upon one leg of a substantially Z-shaped ring member, the other leg of which fits beneath an integral longitudinally projecting flange upon the end-plates of the armature.

My invention may best be understood by reference to the accompanying drawings, in which Figure 1 is a view, in end elevation, with parts broken away for clearness, of a portion of the armature of a dynamo-electric machine embodying my invention. Fig. 2 is a view of a development with parts broken away, of a portion of the cylindrical surface of an armature employing my invention. Fig. 3 is a longitudinal sectional view of a portion of the armature shown in Figs. 1 and 2, and Fig. 4 is a view, with parts broken away, of the details of the joints between the cross connectors and the armature conductors.

Referring to the drawings, an armature core 1 is provided with an end-plate 2 having an integral longitudinally-projecting flange 3. One leg of a detachable ring 4, of substantially Z-shape section, engages a portion of the inner surface of the flange 3, being suitably attached to the end-plate 2 at regular intervals.

The outer portion of the inside surface of

flange 3, in conjunction with the other leg of detachable ring 4, forms a circumferentially disposed recess 5, the walls including which are suitably insulated. The cross connectors 6 are composed of strap conductors 60 disposed on edge, and are appropriately fashioned for progressive connection to armature conductors 7 and for compact nesting within the circumferential recess 5. The connectors 6 severally comprise converging wing portions joined by a longitudinally extending loop 6a. In actual practice, it is found more convenient and stable to lay the cross-connectors 6 edgewise upon the insulated leg of the detachable ring 4, 70 securely bind the nesting wing portions and loops 6a with wire 8, and thus form a compact unit which is placed in engagement with the inside face of the flange 3 and securely held in position, as hereinbefore 75 described.

The suitably drilled ends 9 of the cross-connectors 6 are fastened to the corresponding armature conductors 7 for completing the proper circuits, as shown in Fig. 4. In 80 the particular machine described as embodying my invention, the connections of the cross-connectors 6 and conductors 7, are made as follows:

The conductors 7, forming a coil group 10, 85 have the usual rear end loop 11. The middle conductor 12 is provided with a secondary loop 13 flattened upon itself and projecting radially at right angles to loop 11. The secondary loop 13 is suitably drilled for connection with the appropriately bent ends 90 of the cross-connectors 6.

I do not wish to be restricted to the specific details hereinbefore set forth, but desire that only such limitations be imposed 95 as are indicated in the appended claims.

I claim as my invention:

1. In a dynamo-electric machine, the combination with a rotatable member embodying an end-plate provided with an integral, 100 longitudinally projecting, annular flange, and a winding comprising a plurality of conductors, of a supporting ring partially engaging the inner surface of said flange, a plurality of strap cross-connectors disposed 105 on edge and associated with said conductors, the convergent halves of each connector being disposed inwardly in a longitudinal direction, means for permanently attaching the same to the unengaged portion of said 110

supporting ring, and means for attaching said supporting ring to said end-plate.

2. In a dynamo-electric machine, the combination with a rotatable member embodying an end-plate provided with an integral, longitudinally projecting, annular flange, and a winding comprising a plurality of conductors, of a supporting ring, of substantially Z-shape in cross-section, a portion of which engages the inner surface of said flange and forms a longitudinally-disposed annular recess, a plurality of strap cross-connectors disposed on edge and connected to said conductors, the halves of each connector being centrally convergent and disposed within said annular recess, means for binding said cross-connectors to said supporting ring, and means for attaching said supporting ring to said end-plate.

3. In a dynamo-electric machine, the combination with a rotatable member embodying an end-plate provided with an integral, longitudinally projecting, annular flange, and a winding comprising a plurality of conductors, of a supporting ring of substantially Z-shape in cross-section and having one leg which is fitted tightly within said flange, a plurality of strap cross-connectors disposed on edge and connected to said conductors and severally having the convergent halves disposed inwardly in a longitudinal direction and symmetrically located upon the other leg of said supporting ring, means for securely binding said cross-connectors thereto, and means for attaching said supporting ring to said end-plate.

4. In a dynamo-electric machine, the combination with a rotatable member provided with a winding comprising a plurality of conductors, of an end-plate attached to said member, provided with an integral, longitudinally-projecting annular flange, a ring member having a portion which engages the inner surface of said flange and another portion which is adapted to form an annular recess with said flange for receiving cross-connectors for said conductors, and means for attaching said ring member to said end-plate.

5. In a dynamo-electric machine, the combination with a rotatable member provided with a winding comprising a plurality of conductors, of an end plate attached to said member and provided with an integral, longitudinally-projecting annular flange, a ring of substantially Z-shape in section and having one leg fitted tightly within said flange and the other leg forming an annular recess with said flange for receiving cross-connectors for said conductors, and means for removably attaching said ring to said end-plate.

6. In a dynamo-electric machine, the combination with a rotatable member provided with a winding comprising a plurality of

conductors, of a plurality of cross-connecting members severally comprising converging wing portions, the said members being progressively arranged so that the wing portions thereof form a composite ring-like structure.

7. In a dynamo-electric machine, the combination with a rotatable member provided with a winding comprising a plurality of conductors, of a plurality of cross-connecting members severally comprising converging wing portions, the said members being arranged so that the adjacent wing portions thereof nest together, to form a composite ring-like structure.

8. In a dynamo-electric machine, the combination with a rotatable member provided with a winding comprising a plurality of conductors, of a longitudinally-projecting annular flange attached to said rotatable member, a ring of substantially Z-shape in section and having one leg fitted tightly within said flange and the other leg forming an annular recess with said flange for receiving cross-connectors for said conductors, and means for removably attaching said ring to said rotatable member.

9. In a dynamo-electric machine, the combination with a rotatable member provided with a winding comprising a plurality of conductors, of a longitudinally-projecting annular flange associated with said rotatable member, and a detachable unitary structure for engaging the inner surface of said flange and comprising a supporting means and a plurality of cross-connectors for said conductors disposed on edge and forming a compact unit with said supporting means.

10. In a dynamo-electric machine, the combination with a rotatable member provided with a winding comprising a plurality of conductors, of a longitudinally-projecting annular flange attached to said rotatable member, and a detachable unitary structure fitting closely within said flange and comprising a rigid supporting member and a plurality of cross-connectors for said conductors disposed on edge and permanently bound to said supporting member.

11. In a dynamo-electric machine, the combination of a multi-conductor coil having a longitudinally projecting end loop, one conductor thereof having an additional transversely extending portion, and a cross-connecting member electrically connected to said portion.

12. In a dynamo-electric machine, the combination of a multi-conductor coil having a longitudinally projecting end loop, one conductor thereof having a transversely-extending flattened loop, and a plurality of cross-connecting members electrically connected to said second loop and extending in opposite directions.

13. In a dynamo-electric machine, the

combination with a magnetizable core having a plurality of slots, and a plurality of multi-conductor coils severally disposed in corresponding pairs of said slots and having longitudinally projecting end loops, one conductor of each of said loops having a radially-extending flattened loop, and a plurality of circumferentially-disposed cross-connectors having their ends severally secured to

10 corresponding flattened loops.

14. In a dynamo-electric machine, the combination with a magnetizable core having a plurality of slots, and a plurality of multi-conductor coils severally disposed in

15 corresponding pairs of said slots and having longitudinally projecting end loops, an inter-

mediate conductor of each of said loops having a flattened loop extending radially inwardly from the end of the associated end loop, and a plurality of circumferentially- 20 located, edgewise-disposed cross-connectors severally having their ends secured to corresponding flattened loops and collectively adapted to form a compact nesting structure.

In testimony whereof, I have hereunto 25 subscribed my name this 9th day of January 1913.

GEORGE H. KRAUSKOPF.
